UNITED STATES PATENT OFFICE.

HENRY F. SCHURMANN, OF WILMETTE, ILLINOIS, ASSIGNOR TO W. A. SCHURMANN & CO., OF CHICAGO, ILLINOIS, A CORPORATION OF ILLINOIS.

BOX OR CARTON.

Application filed December 6, 1922. Serial No. 605,146.

To all whom it may concern:

Be it known that I, HENRY F. SCHURMANN, a citizen of the United States, and resident of Wilmette, Cook County, Illinois, have invented a certain new and useful Improvement in Boxes or Cartons, of which the following is a specification.

This invention relates to boxes or cartons in general, but more particularly to those for eggs, such as those in which a dozen eggs carried by a filler are delivered to a customer. These boxes or cartons are made from a paper blank, ordinarily, and are so constructed that they will fold flat, thus permitting the manufacturer to stack the cartons flatwise together, and to thus economize in the cost of shipment.

Generally stated, the object of the invention is to provide an improved construction and arrangement, and an improved method of folding the carton, whereby certain beneficial results are obtained.

It is also an object to provide certain details and features of construction tending to increase the general efficiency and desirability of a carton of this particular construction.

To the foregoing and other useful ends the invention consists in matters hereinafter set forth and claimed and shown in the accompanying drawings in which—

Figure 1 is a perspective of a carton embodying the principles of the invention, showing the cover partially closed, and showing a portion of the cover broken away for convenience of illustration.

Figure 2 is a similar view showing the new method of folding the carton into a flat condition.

Figure 3 shows the carton folded flat.

Figure 4 is an enlarged detail section on line 4—4 in Figure 3.

Figure 5 is a plan view, on a smaller scale, of one of the blanks from which the carton is made, showing a portion of the cover section broken away for convenience of illustration, as is also true in said Figure 3 of the drawings.

As thus illustrated, the invention comprises a blank as shown in Figure 5 having a rectangular bottom section 1, rectangular side sections 2 and 3, rectangular end sections 4 and flaps 5 and 6 flexibly connected to the ends of said side sections. It will be understood that the rectangular bottom and

side and end sections are flexibly connected together by the crease lines 7, 8 and 9, and that the flaps 5 and 6 are flexibly connected by the crease lines 10 and 11 with their respective side walls. The lines 12 and 13 are cut clear through, so that the blank may fold in the desired manner. The flaps 5 have oblique crease lines 14 as shown. Also, the front side wall 3 of the carton has crease lines 15 as shown. In addition, a rectangular cover section 16 is provided and flexibly connected by the crease line 17 to the rear side section 2 previously mentioned. Finally, a cover flap 18 is flexibly connected by the crease line 19 to the rectangular cover section, said flap 18 having curved end edges 20 as shown, so that this flap will enter the top of the box easily and gradually exert wedging pressure against the end walls of the carton.

In making the carton, the blank thus constructed is folded up in the manner shown in Figure 1, so that the flap 6 overlaps the flap 5, at each end of the box, and a staple 21 is then inserted through the overlapping flaps and end walls at opposite ends of the box, in order to hold the blank in folded condition. Of course, it is obvious that other fastening means may be employed if desired. When thus folded the flap 18 of the cover may be brought down to enter the interior of the box, and the cover section 16 will lie flat over the eggs and the egg filler (not shown) in the usual and well known manner. But the width of the flap 18, which is just a little less than the depth of the box, and its gradually curved edges at the ends thereof, will ensure not only proper entrance of the flap into the box, but also tends to ensure against pulling out after the box is closed.

Now for shipping purposes the cartons are knocked down or folded flat as shown in Figure 3, and this is done in the manner illustrated in Figure 2, from which it will be seen that the end walls 4 are not creased, but folded perfectly flat against the bottom of the box, with the exception of the section of each end wall which is folded between the flap 6 and the triangular sections 22 of the front wall 3 of the box. The balance of each end wall 4 rests directly against the bottom wall of the box, and the outer surfaces of the flaps 6, while the exposed outer surfaces of the end walls 4 receive the inner

surface of the back wall 2 directly thereon. Now by not creasing the end walls 4 the general scheme of the box works better, as these two rectangular end walls remain flat and more or less rigid and hold the ends of the box in proper form or condition, much better than would be the case with the end walls 4 creased (so that they would fold along the lines 14) and in addition the uncreased end walls permit the box to be folded flatter and they tend to remain flat. When the box is opened up, the uncreased end walls 4 act as braces to resist the inclination of the box to collapse or fold back into flat condition.

Thus it will be seen that the rectangular uncreased end walls 4 serve as stiff braces between the front and rear walls 3 and 2, or between the front and back of the box, when the box is open or unfolded. In other words, if these walls 4 are creased they do not form stiff braces between the front and back walls, and cannot serve as such, and they cannot perform this function unless they reach from the front wall to the back wall of the box, in the manner shown. Furthermore, the flap 18 forms a stiff brace between the end walls of the box, to keep the creased front wall 3 straight, when the box is closed. With the box creased as shown, for folding purposes, it has a tendency to assume its folded or flat condition, when unfolded, but the walls 4 and the flap 18 each serve as a stiff brace to resist this inclination of the box to collapse or fold into a flat condition after being unfolded, and after being filled and closed.

The uncreased end walls 4 serve, therefore, as stiff braces or spacing members to space the front and rear walls of the box apart and hold them upright when the box is open. Thus the box will stand alone, in open condition, before the egg filler or other contents of the box is inserted, notwithstanding the creases 14 and 15 which permit the box to collapse and to be folded flatwise for certain purposes. Thus the box is a rigid rectangular structure when open, before the filler or other contents is inserted, and in addition the box is a better protection for the things placed therein.

With the creases 15 in the front wall, the inclination of this wall, when the box is open, is to spring inward, thus throwing the triangular sections 12 into position to hold the adjacent edges of the uncreased inner end walls 4 in position, so that these end walls 4 can then serve their function of forming stiff braces between the front and back walls, and whereby when the box is open, the end walls do not spring inward, inasmuch as the uncreased walls 4 are held in their vertical positions by the pressure of their edges on the triangular sections 22 of the front wall. Also, the edges 20 engage

the uncreased sections 4, so that when the box is closed, the uncreased sections 4 and the flap 18 co-operate to render the box stiff and rigid.

Thus it will be seen that the triangular portions 22 function, when the box is in the condition shown in Fig. 1, before it is filled, to hold the uncreased rectangular end walls 4 in position to brace the box and keep it open to receive the egg filler or other means to be placed in the box. The creased side wall 3, of course, tends to spring inwardly, and hence the triangular sections 22 tend to keep the uncreased end walls 4 in upright position, or at least against the flaps 6, so that the box cannot collapse before it is filled. Of course, after the box is filled, and after the cover is closed, the wedging action of the flap 18 and its edges 20 against the end walls 4 serve to hold the latter upright, and serve to hold the front wall 3 and its triangular sections 22 against collapsing inwardly, in the manner explained. In the engagement of the uncreased rectangular end walls 4 with the back wall 2, and in the engagement of the triangular portions 22 with the front edges of the front wall 3, there is co-operating action serving to prevent the box from collapsing after it is opened, and before it is filled, and such action co-operates with the cover and the flap 18 after the box is filled, thereby to brace the box and hold it in shape after the contents are enclosed therein. Preferably, as shown, the flaps 6 overlap the flaps 5, so that a single staple is sufficient at each end of the box, and the flaps 5 are creased at 14 to fold over the uncreased flaps 6, substantially in the manner shown and described, whereby each end wall construction has only the single crease 14, the upper corner of each flap 6 being cut off as shown to permit the folding of the flaps 5 along their crease lines 14, as shown in Figs. 2 and 4, when the box is collapsed and flattened out for shipment or storage or transportation.

Thus it will be seen that only the rear edges of the uncreased end walls 4 have sliding engagement with the rear of the box, when the carton is folded or unfolded. The front edges of the rectangular uncreased sections 4 have no sliding engagement with the inner surface of the box, inasmuch as the rectangular sections 22 hold these front edges always in engagement with the fold lines 11 of the flaps 6 of the blank from which the carton is made. Hence, when the carton is unfolded, the endwise expansion of the front wall 3, so to speak, or the unfolding of this wall, serves forcibly to propel the end walls 4 away from each other, whereby this straightening of the front wall 3 constitutes the means for forcibly causing the rear edges of the end walls 4 to slide

upon the inner surface of the back wall 2, when the carton is unfolded. Of course, this sliding action of the rear edges of the walls 4 on the back wall 2, when the carton 5 is unfolded, can be brought about by forcibly pulling outwardly on the walls 4 and 4, as by placing a thumb inside of each end wall, but in any event the endwise expansion of the wall 3, or its unfolding motion, 10 is productive of or accompanied by the forcible sliding of the rear edges of the wall 4 on the inner surface of the wall 2 of the carton.

Thus when the box is open the rear edges 15 of the walls 4 engage the fold lines 10, or engage in the corners formed by these fold lines, while the front edges of the walls 4 engage in the corners formed by the fold lines 11 at the front of the box. However, 20 when the box is folded flat, the front edges of the walls 4 remain in engagement with the fold lines 11, but the rear edges of the walls 4 then engage the fold line 7 between the back 2 and the bottom 1 of the box. 25 Thus the front edges of the walls 4 are always in engagement with the fold lines 11, and when the box is opened this tends to

keep the rear edges of the wall 4 in engagement with the fold lines 10, in the manner shown and described.

30

What I claim as my invention is—

A collapsible box or carton formed from an integral folded blank and comprising bottom, front and back walls, rectangular end sections on said bottom extending the full width thereof, said sections being uncreased, the said end sections thereby retaining a relatively rigid character to brace the end structure of the box, a flap on each end of said front and back walls, each front flap being adapted to overlap the corresponding rear flap outside of said end sections, means for fastening said overlapping flaps to the adjacent end section near the center thereof, an oblique crease in each of said rear flaps, the front flaps being uncreased, and an oblique crease at each end of said front wall, whereby when said box is folded the front wall will be folded inwardly to form a triangular portion at each end lying between the adjacent end section and the bottom, the remainder of said end sections being in contact with the bottom.

HENRY F. SCHURMANN.
